DESIGN FOR A COMBINED CLOSURE MEMBER AND FRAME FOR A LADY'S HANDBAG

Georges Chaumet, Paris, France

Application September 14, 1935, Serial No. 58,553

Term of patent 3½ years

To all whom it may concern:

Be it known that I, Georges Chaumet, a citizen of the French Republic, residing at 45, Avenue des Accacias, Paris, France, have invented a new, original, and ornamental Design for a Combined Closure Member and Frame for a Lady's Handbag, of which the following is a specification, reference being had to the accompanying drawing, forming part thereof.

In the accompanying drawing there is shown an ornamental design for a combined closure member and frame for a lady's handbag in which Fig. 1 is a front elevational view and Fig. 2 is a side view with the frames partially separated or in the open position.

I claim:

The ornamental design for a combined closure member and frame for a lady's handbag, substantially as shown and described.

GEORGES CHAUMET.
